UNITED STATES PATENT OFFICE

141,085

DESIGN FOR A TRUCK

John J. Powers, St. Louis, Mo.

Application February 12, 1945, Serial No. 117,903

Term of patent 14 years

(Cl. D14—3)

To all whom it may concern:

Be it known that I, John J. Powers, a citizen of the United States, residing at the city of St. Louis, State of Missouri, have invented a new, original, and ornamental Design for a Truck, of which the following is a specification, reference being made to the accompanying drawings, forming a part thereof, in which Figure 1 is a front perspective view of a truck showing my new design; Figure 2 is a rear perspective view with the closure curtain in lowered position; Figure 3 is a rear perspective view with the closure curtain in rolled up position; and Figure 4 is a rear perspective view thereof.

I claim:

The ornamental design for a truck, substantially as shown.

JOHN J. POWERS.
